UNITED STATES PATENT OFFICE.

FRANK H. ALDER, OF ST. LAMBERT, QUEBEC, CANADA, ASSIGNOR TO WESTERN ELECTRIC COMPANY, INCORPORATED, OF NEW YORK, N. Y., A CORPORATION OF NEW YORK.

TELEPHONE INSTRUMENT.

Application filed January 10, 1923. Serial No. 611,839.

To all whom it may concern:

Be it known that I, FRANK H. ALDER, a subject of the King of Great Britain, residing at St. Lambert, in the Province of Quebec, Dominion of Canada, have invented certain new and useful Improvements in Telephone Instruments, of which the following is a full, clear, concise, and exact description.

10 This invention relates to telephone substation apparatus; and its object is a switching mechanism therefor which will prevent the sending of false impulses and the causing of premature disconnections by incomplete movements of the switchhook in either direction, and which will be easy to install, to modify, and to maintain.

20 In accordance with one of the features of the invention, there is provided switching mechanism comprising a rotatable shaft operated by the switchhook lever against the action of a restoring spring, and operating the contact springs at a predetermined time in the switchhook movement through the 25 medium of a lost motion switching means.

Other features of the invention relate to details of the construction and combination of parts which render both the terminal plate supporting the contact springs, and the 30 transmitter and switchhook supporting mechanism readily removable from the base and stem of a desk stand.

The drawing shows a telephone desk stand embodying the invention.

35 Fig. 1 is a side view of the desk stand with part of the covering removed to reveal the operating mechanism.

Fig. 2 is a bottom view of this mechanism.

40 Fig. 3 is a front view of the switchhook and its associated mechanism.

Figs. 4 to 6, respectively, show the switchhook in its normal position, in a considerably higher position, and at the completion of its upward swing; while Figs. 7 to 9 show the 45 corresponding positions of the delayed action switching mechanism in the base of the desk stand.

Fig. 10 shows the desk stand base and stem with the transmitter and switchhook assembly, the terminal plate, and the base plate removed.

50 Fig. 11 shows the transmitter and the switchhook mechanism removed from the desk stand stem.

Fig. 12 shows the terminal plate and 55 spring pile-up removed from the desk stand base.

Fig. 13 shows the base plate removed from the base.

Fig. 14 is a detail end view of the spring 60 actuating mechanism.

The desk stand comprises a transmitter 5 mounted on a holder 6 which fits into the top of a stem 7 mounted on a base 8 which rests on a base plate 9. A nut 10 which holds the stem 7 on the base 8 also holds in place a washer 11 on which are lugs 14 which hold the base plate 9 in place, and lugs 16 which hold in place a terminal plate 25. A calling dial 19 is set into the 70 forward surface of the base 9. A switchhook 12 is pivoted to the transmitter holder 6 at 13 and an extension 15 at its inner end is adapted to bear on a bent-over end 17 of a vertical shaft 18 in stem 7, so as to rotate 75 the shaft upon the depression of the switchhook. Shaft 18 is held in place by projecting lugs 49 on a supporting plate 20, to the upper end of which the transmitter holder 6 is fastened. The end 17 of shaft 18 is 80 caused to bear against the extension 15 on the switchhook 12 by a restoring coil spring 21 which is formed about the shaft with its upper end attached to a sleeve 22 about the shaft and its lower end attached 85 to supporting plate 20. This spring may be tensioned for use under varying operating conditions by the adjustment of the sleeve 22 which has notches therein adapted to fit over the ends of a pin 23 in shaft 18. Supporting 90 plate 20 is fastened to the terminal plate 25 by means of a single screw 28 extending through the terminal plate into a lug (not shown) extending to the right from the foot of plate 20. Upon terminal plate 25 is 95 spring pile-up 29 comprising contact springs 31, 32 and 33 which are arranged to close the line circuit when the receiver is removed from the switchhook, and to open it when the hook is fully depressed by the weight of 100 the receiver.

Rotatably mounted on the lower end of the rod 18, which projects through an opening 37 in the terminal plate 25, and in proximity to spring 31 is a radial arm 34 to which is 105 attached a vertical stud 35. Arm 34 fits slidably into a rectangular slot in a bent-over end of a radial plate 36 which is fixedly

mounted on the rod 18. Stud 35, when actuated by the raising of the switchhook, bears against an outwardly projecting bend or hump 38 on spring 31 to actuate it. The 5 movement of stud 35 is limited by projections 39 and 40 on a plate 41 mounted in the spring pile-up. The opening 37 in the terminal plate is made large enough to permit the withdrawal of the radial members 34 and 10 36 therethrough when it is desired to remove the switchhook assembly from the stem 7 or to remove the terminal plate from the base 8.

The delayed action switching mechanism 15 operates as follows:

Assume that a receiver is on the switchhook which is in the position shown in Fig. 4. Radial members 34 and 36 will be at the right, stud 35 will be at the right of bend 38 20 and bearing against projection 39 on plate 41, and the springs 31, 32, and 33 will be apart, as shown in Fig. 7. Suppose, then, that the receiver is accidentally lifted so that the switchhook rises to the position 25 shown in Fig. 5. The rod 18 will be permitted to rotate under the influence of spring 21 so as to carry the fixedly mounted radial plate 36 part way to the left, as shown in Fig. 8. Rotatably mounted radial arm 30 34, however, will not be disturbed, stud 35 will still be at the right of bend 38, and no contact is made between the springs. If, 35 on the other hand, the receiver is completely removed from the hook, in order to call a party, the switchhook will rise to the position shown in Fig. 6, the radial plate 36 will be rotated further to the left now carrying with it a radial bar 34 so that stud 35 will bear against the bend 38 so as to actuate the 40 contact springs. The stud comes to rest against projection 40 and plate 41 in a position just left of the vertex of bend 38 so that contact between the springs will be maintained until positive pressure is brought 45 to bear on arm 34 to move it to the right. The switching mechanism operates in a similar manner when the switchhook is lowered. Only when the lowering of the switchhook is substantially complete, will radial plate 36 begin to carry bar 34 to the 50 left with it so as to open the circuit.

The invention claimed is:

1. In a telephone instrument, a switchhook having a limited movement, contact springs, a shaft rotatable by the switchhook extending between the switchhook and the springs, and switching means upon the shaft for actuating the springs in response to only the latter part of the movement of the switchhook in either direction.

2. In a telephone desk stand, a stem, a switchhook, contact springs, delayed action switching means for causing contact between the springs in response to the latter part of the switchhook movement, and a shaft in the

stem rotated by the switchhook for actuating said switching means.

3. A telephone desk stand comprising a base, a stem, a movable switchhook, contact springs in the base, a rotatable shaft in the 70 stem actuated by the switchhook, delayed action switching means controlled by the shaft for actuating the springs in response to the latter part of the switching movement.

4. In a telephone desk stand, a base, a 75 stem, a switchhook having a limited movement, a vertical shaft in the stem rotatable in one direction by the switchhook, a coil spring about the shaft to rotate it in the other direction, means on the shaft for adjusting the tension of the coil spring, contact springs in said base, and switching means in the base to actuate the contact springs only in response to a substantially 80 complete movement of the switchhook.

5. In a telephone desk stand, a base, a 85 stem, a shaft in the stem, a switchhook to rotate the shaft in one direction, a coil spring about the shaft to rotate the same in the other direction, a radial arm rotatably mounted on the foot of the shaft, contact springs in the base in operating relation to the arm, and means rigidly secured to the shaft to rotate the arm and operate the springs toward the end of a rotation of the 90 shaft in either direction.

6. In a telephone desk stand, a base, a 95 stem, a vertical shaft in the stem, a switchhook lever to rotate the shaft in one direction, a coil spring about the shaft to rotate it in the other direction, a pin through the shaft, a sleeve about the shaft to which the coil spring is attached, notches in the sleeve to fit over the ends of said pin so as to permit the tension of the coil spring to be varied, 100 contact springs in the base, and switching means on the shaft to actuate the contact springs only in response to the latter part of the 105 switchhook movement.

7. In a telephone desk stand, a base, a 110 stem, a switchhook having a limited movement, a vertical shaft in the stem rotatable by the switchhook, a coil spring about the shaft, a pin through the shaft above the coil spring, an adjustable member for the spring having notches therein to fit over the ends of the pin, contact springs in said base and radial arms on the bottom of the shaft for actuating the contact springs only in response to a substantially complete movement 115 of said switchhook in either direction.

8. In a telephone desk stand, a base, a 120 stem, a switchhook having a limited movement, a vertical shaft and a supporting plate therefor in said stem, adjustable means for causing the shaft to bear against the switchhook so as to be rotated by the movement thereof, a terminal plate in the base of the 125 desk stand, contact springs on the terminal plate, and means comprising said shaft for 130

actuating the contact springs in response to the latter part of the switchhook movement.

9. In a telephone desk stand, a base, a stem, a terminal plate in the base, a shaft in 5 the stem projecting through the terminal plate, a switchhook to rotate the shaft in one direction, a coil spring to rotate it in the other direction, contact springs on the lower side of the terminal plate, an outwardly 10 projecting bend on one of the springs, a radial arm rotatably mounted on the foot of the shaft in operating relation to said outwardly projecting bend, means rigidly secured to the shaft to rotate the arm and operate the springs during the latter part of 15 the rotation of the shaft in either direction, and means to prevent the operation of the arm except from the operation of the first mentioned means.

10. In a telephone desk stand, a base, a stem, a switchhook, a supporting plate in the

stem, a shaft mounted on the supporting plate and rotatable in accordance with the switchhook movement, a radial plate having a rectangular slot in a bent-over portion thereof fixedly mounted to the foot of the shaft and set slidably in said slot, a stud in the end thereof, a terminal plate in said base, an opening therein through which the bottom of the shaft carrying the radial member 25 projects, a screw for attaching the terminal plate to the supporting plate, contact springs on the lower side of the terminal plate, an outwardly projecting bend on one of said springs, and means to maintain the 30 pressure of the stud on said bend until the movement of the radial arm by the radial plate.

In witness whereof, I hereunto subscribe my name this third day of January, A. D. 40 1923.

FRANK H. ALDER.
